UNITED STATES PATENT OFFICE

160,340

HANDLE POST

Max H. Randolph, New York, N. Y.

Application March 22, 1950, Serial No. 8,692

Term of patent 7 years

(Cl. D87—2)

To all whom it may concern:

Be it known that I, Max H. Randolph, a citizen of the United States, residing in the city, county, and State of New York, have invented a new, original, and ornamental Design for a Handle Post, of which the following is a specification, reference being had to the accompanying drawing, forming a part hereof, in which:

Fig. 1 is a front elevational view of a handle post embodying my new design.

Fig. 2 is a right hand side elevational view thereof.

Fig. 3 is a left hand side elevational view thereof.

I claim:

The ornamental design for a handle post, as shown:

MAX H. RANDOLPH.
